PETER H. BAACK, OF SAN FRANCISCO, CALIFORNIA.

SCREEN-RIM.

988,296.

Specification of Letters Patent.

Patented Apr. 4, 1911.

Application filed November 22, 1910. Serial No. 593,635.

To all whom it may concern:

Be it known that I, PETER HENRY BAACK, a citizen of the United States, residing at San Francisco, in the county of San Francisco and State of California, have invented 5 new and useful Improvements in Screen-Rims, of which the following is a specification.

The present invention relates to an im- 10 proved screen rim.

It is a matter of common experience that all screens wear out much sooner in the screening or perforated portion thereof than in the rim or unperforated portion. This 15 being the case it is obviously of great utility to provide a screen having a perforated or screening portion detachably connected to the rim or unperforated portion, so that the former can be replaced by other screening 20 material when worn out. This detachability is also very desirable on account of the advantage thereby obtained of being able to use screening material of any desired mesh with the same rim, thereby greatly saving in 25 expense. Notwithstanding the great utility of such construction, no device of this kind is extensively, if at all, on the market. The reason undoubtedly is the difficulty of providing a connection between the screening 30 material and the rim portion which will permit them to be detached from one another and will yet hold them together very securely when in use. In my improvement I provide a means for overcoming this diffi- 35 culty.

In the accompanying drawing, Figure 1 is a transverse section of a screen constructed in accordance with my invention; Fig. 2 is a broken plan view thereof; Fig. 3 is an 40 enlarged detail section showing more particularly the groove and teeth.

Referring to the drawing, 1 indicates an outer rim section and 2 an inner rim section, fitting closely within the outer section. 45 Said sections are here shown as round, but they may be made square or oblong or of any desired form. Said sections are slightly conical at their upper or larger ends, and are formed with flanges 3, 4, having co-register- 50 ing holes 5 through which are passed bolts

6 on which are screwed nuts 7 to hold said flanges together.

8 indicates screening material, here shown as of wire cloth, although it may be made of cheese cloth or any other desired sheet ma- 55 terial having perforations.

The outer rim 1 is formed at its lower or smaller end with an inwardly and upwardly extending flange 10 forming a groove 11, and over the edge of said flange and on said grooved portion is laid the marginal portion 60 of the screen 8. The lower or smaller end of the inner rim is formed with teeth 13. When the rims are secured together by means of the bolts said teeth 13 press the 65 marginal portion of the screen 8 into said groove 11 and secure it therein.

I find that by the above construction the screen is very firmly secured to the rim, whereas all other constructions, of a simple character, which permit the screen to be detached from the rim, do not hold it with sufficient security when attached. Even if the lower edge of the inner rim presses the margin of the screen into the groove it will 70 not hold it with absolute security against great strain upon the screen unless it be serrated as shown, although it may hold it sufficiently well when there is not such strain thereon, and therefore I regard it as with- 75 in the scope of my invention, although an inferior form thereof.

By this construction I greatly economize in the cost of using screens; first, because when the screen proper is worn out it may 80 be replaced by a new one at trifling expense without having to renew the rim; second, be- 85 cause screens of a large number of different meshes may be kept on hand without re- quiring a rim for each screen; third, the ex- 90 pense of transportation and storage of screens is greatly reduced.

I claim:

The combination of an outer rim, formed at its lower end with an inwardly and up- 95 wardly extending flange forming a groove, a screen, a marginal portion of which is laid over the edge of said flange and on said grooved portion of said outer rim, an inner rim, the lower end of which is formed with 100

teeth received between said flange and the main portion of the outer rim, and engaging the marginal portion of the screen, said inner and outer rims being formed at 5 their upper ends with outwardly extending flanges, and bolts for pressing said latter flanges closely together, substantially as described.

In testimony whereof I have hereunto set my hand in the presence of two subscr- 10
ing witnesses.

PETER H. BAACK.
